UNITED STATES PATENT OFFICE

SAMUEL J. DAVENPORT AND JOHN WARD, OF ALBANY, NEW YORK.

IMPROVEMENT IN PAVEMENTS.

Specification forming part of Letters Patent No. 143,965, dated October 28, 1873; application filed November 23, 1872.

To all whom it may concern:

Be it known that we, SAMUEL J. DAVENPORT and JOHN WARD, of the city and county of Albany, State of New York, have invented certain new and useful Improvements in Stone and Concrete Pavements; and we do hereby declare that the following is a description thereof, reference being had to the accompanying drawings forming a part of this specification, in which—

Figure 1 represents a perspective view of a section of the pavement embodying the improvements in this invention and illustrating the several stages of progress of the same. Fig. 2 is a sectional elevation of the same. Fig. 3 is a plan of the same illustrated in a section of the pavement.

Our invention relates to a stone and concrete pavement; and consists in the combination of a coarse concrete bed, formed of coal-tar and coarse gravel with a hard rammed or pressed earth bed, stones, and interstices of coarse concrete, in such a manner that the concrete bed will serve as an elastic cushion between the stones and the earth, and the concrete interstices will unite with the said concrete bed and with the stones, so as to be capable of preventing the water getting between the same, and the whole mass will become as one piece, possessing, to a degree, an elastic nature, which will render the pavement easier to the feet of animals, and, also, will greatly tend to deaden the sound of vehicles. It further consists in the combination of a thin layer of fine concrete, made of distilled coal-tar and fine gravel with stones embedded in an elastic bed of coarse concrete, and their interstices filled with concrete, in such a manner that the top surface of the pavement will be made comparatively smooth and even, while the stones will be just covered and rendered capable of taking the wear of travel, leaving the surface concrete to shed the water and render the foothold of the animals firm and not liable to slip, while the whole mass will become as one body.

To enable others skilled in the art to make and use our invention, we will proceed to describe it in reference to the drawings and the letters of reference marked thereon, the same letters indicating like parts.

In the drawings, A represents the properly-

graded street bed, on which the pavement is laid, the surface sand or earth of which we ram or roll very hard and even. We then lay on the said hard rammed or rolled bed a second bed, B, which we denominate the elastic concrete cushion, which consists of a layer of coarse concrete made of coal-tar, and coarse gravel well mixed up together and of a stiff consistency. The said bed of concrete is laid about six inches, more or less, in an even manner over the whole earth bed A, as shown. On the said concrete bed or cushion are laid the stones C C, which may be either the common cobble-stones, as shown in Figs. 1, 2, and 3, or what are termed the Belgian stone, or any other suitable stones used for paving. The said stones are properly set in the concrete layer B and rammed down so as to sink, if cobble-stones, about from one and one-half to two inches into the said concrete bed, as shown in Figs. 1 and 2. If Belgian stones are used they are also rammed, so as to be firmly set into the concrete, though by the nature of their surface they cannot be made to sink like the cobble-stones into the said bed. When the stones C have been properly set and rammed, as shown in the section 1 in Fig. 1, we fill the interstices a a between the stones with the same coarse concrete composing the bed B, as shown by section 2 in Fig. 1, and also in Figs. 2 and 3. The concrete is to be put in hot or cold, according to the weather or the season, and well rammed, so as to completely fill the interstices and make the said fillings solid. The said concrete interstices are not, with cobble-stones, made to fill up to the apex of the same, but to a little distance from a line with the same, as in section 2, Fig. 1, and in Fig. 3. After the pavement has been brought to this stage in its progress, we slush the whole surface of the pavement with coal-tar, applied either hot or cold, according to the weather and season, in such a manner that the projecting surface of the stones, and also the concrete interstice fillings will be completely covered over. The coal-tar acts as a binding cement to cause the top dressing D to adhere firmly to the stones and concrete filling, and thus overcome the liability of the top dressing to scale off, and, when the pavement is finished, causes it to be as if it were one homogeneous mass, in which each

part is made to cling and hold to the other. We then make a fine concrete of chemical (distilled) tar and fine gravel or coarse sand, or both, which is applied to the top surface of the pavement, either hot or cold, according to the season or weather, in an even and uniform manner, so as to just cover over the tops of the stones, as left in section 2 in Fig. 1, after the interstices have been filled, so as to make a level surface, as shown by section 3 in Fig. 1, and in Fig. 2. After the surface has been thus slushed or filled with the said layer of fine concrete it is rolled down with heavy rollers and permitted to set and dry or season.

This pavement by the improvements has the superior advantages over other pavements made with stone and concrete, because of the elastic concrete cushion B interposed between stones and the sand below, which not only prevents the water getting beneath the stones to effect the sand bed A, but gives to the pavement an elastic support which prevents the usual jar and noise usually attending stone pavement, and also renders the pavement easier to the animal's feet; by the interstices being filled no water can get between the stones to effect the setting of the same, and by the top dressing of the fine concrete the top surface is

made firm for the animal's foothold, while the tops of the stones are rendered capable of receiving all the wear of the pavement.

The pavement thus made forms a firm mass having an elastic bottom with a substantial wearing upper portion having a surface which will be at once durable and easy for travel.

Having described our invention, what we claim, and desire to secure by Letters Patent, is—

1. In a pavement, the combination of the upper fine concrete dressing D and coarse concrete interstices a, with the stones C, elastic concrete bed B, and packed earth bed A, substantially as and for the purpose set forth.

2. In a concrete stone pavement having the interstices of the stones filled with concrete, and a top dressing, D, the slushing of the top surface of the pavement immediately after the filling of the interstices and before the application of said top dressing with coal-tar, applied either cold or hot, as described, for the purpose set forth.

SAMUEL J. DAVENPORT.
